(57) **CLAIM**

The ornamental design for an air conditioner unit for a vehicle, as shown and described.

DESCRIPTION

FIG. 1 is a left, front perspective view of an air conditioner unit for a vehicle according to my novel design, the right, front perspective view being mirror symmetrical;

FIG. 2 is a left side view thereof, the right side view being mirror symmetrical;

FIG. 3 is a top view thereof;

FIG. 4 is a front view thereof;

FIG. 5 is a rear view thereof; and,

FIG. 6 is a left, front perspective view thereof, the right, front perspective view being mirror symmetrical. This figure shows the placement of the invention on the vehicle.

The broken lines are for illustrative purposes only and form no part of the claimed design.
